M. BUCH.
FOLDING TOP.

APPLICATION FILED APR. 24, 1919.

1,285,922.

Patented Nov. 26, 1918.

Inventor:

Max Buck,

By Spear Middleton Donaldson of Spear
Attoe.

UNITED STATES PATENT OFFICE.

MAX BUCH, OF DETROIT, MICHIGAN, ASSIGNOR TO HENRY E. EDWARDS, OF JACKSON,
MICHIGAN.

FOLDING TOP.

1,285,922.

Specification of Letters Patent. Patented Nov. 26, 1918.

Original application filed October 22, 1917, Serial No. 197,936. Divided and this application filed April 24, 1918. Serial No. 230,492.

To all whom it may concern:

Be it known that I, MAX BUCH, a subject of the Emperor of Germany, and resident of Detroit, Michigan, have invented certain new and useful Improvements in Folding Tops, of which the following is a specification, this application being a division of an application filed by me on the 22d day of October, 1917, Serial Number 197,936.

10 My invention relates to improvements in folding tops for motor vehicles and the like, and aims to provide an extremely simple and economical top which shall be self supporting during its folding and projecting movements, thus enabling it to be operated easily by a single individual, and the folds of the covering material to be properly arranged.

The invention also aims to provide a construction in which the liability of damage 20 to the covering material in the closed position of the top will be reduced to a minimum.

With these and other objects in view, the invention includes the novel features of construction and arrangement and combination 25 of parts hereinafter described, my said invention being defined by the appended claims.

An embodiment of my invention is illustrated in the accompanying drawing, in 30 which, the figure is a side elevation of a top showing the same in full lines in extended position, and in dotted lines in partially folded condition.

In these drawings the top being shown in 35 side elevation, only the standard, bow arms, etc., on one side appear, but it will be understood that they are duplicated on the other side, only one side being shown for convenience.

40 Similarly in the following description and claims reference is made, for convenience, to the members on one side only.

In the drawing the numeral 1 designates the body of the vehicle for which the top is 45 adapted, and which is intended to be representative of any type of vehicle, or motor boat needing such a protective covering. The top covering material is indicated at 2 supported by the folding frame hereinafter 50 described.

This comprises a main standard 3 designed to have its lower end pivotally supported in any suitable manner from the vehicle body, as indicated for example at 3^a,

and designed to coöperate with one end or 55 arm of the usual rear bow arm 4, which may be pivoted to the standard at 4^a. It will be obvious, however, that if desired the rear bow arm might be pivoted to the body and the standard to the bow arm.

5 designates the outrigger bow or arm thereof which has its rear end pivotally connected to the front end of a link or member 6 by preferably a lock joint as indicated at 6^a.

This extended part is intended for direct connection with a cover supporting bow, and in my preferred embodiment the link or member is so curved as to cause the part 6^a to incline upwardly, and serve as a bow arm, 70 and in an all steel top the link, bow arm and bow would all be formed as a continuous piece, this being true of all the bow arms and bows in an all steel construction. Where wood bows are used, however, it will be understood that the metal part, such as the extension of the link 6, would be provided 75 with a socket or other approved means for attachment to the curved part or arm of the bow.

The standard 3, as shown, is inclined forwardly from its pivot, and when the joint 6^a is broken downwardly in folding, the pull of the top covering upon the extension 6^a serves to balance the front extension and enable it 85 to be moved back, from one side only, into the position shown in dotted lines, when it will be self-supporting, permitting the operator to properly arrange the cover material preparatory to folding the top completely back.

If desired an intermediate front bow arm 7 may be provided, which may have its end or arm, pivoted to link 6, as indicated at 7^a.

What I claim is:

1. In a folding top, a supporting standard, an outrigger bow arm, a link pivotally connected at one end to the end of said outrigger bow arm and to said standard by a fixed pivot and having a part extended beyond its point of pivotal connection with the standard, and a free cover supporting bow rigid with said extended part.

2. In a folding top, a standard adapted to be pivotally supported from a vehicle body, 105 an outrigger bow arm, a link pivotally connected to the end of said outrigger bow arm and by a fixed pivot, and to said standard and

- having a part extended beyond its point of pivotal connection with the standard, and a free cover supporting bow rigidly carried by said extended part.
5. In a folding top, a standard, an outrigger bow arm, a link pivotally connected to the said outrigger bow arm and to said standard by a fixed pivot and having a part extended beyond its point of pivotal connection with the standard, and a free cover supporting bow arm forming a continuation of said extended part.
10. In a folding top, a standard, an outrigger bow arm, a substantially horizontal link or member articulated to the end of said outrigger bow arm and to said standard at the upper end thereof by a fixed pivot, said member projecting rearwardly of the standard and having its rear part inclining upwardly to form a cover supporting bow arm.
15. In a folding top, a supporting standard,
20. In a folding top, a supporting standard,

an outrigger bow arm, a link pivotally connected at one end to the end of said outrigger bow arm by a lock joint and to said standard at the other end, and having a part extended beyond its point of pivotal connection with the standard and positioned to form a cover supporting bow arm.

25. In a folding top a forwardly inclined standard and a rearwardly inclined main bow arm adapted to be pivotally supported from the vehicle body, a substantially horizontally disposed outrigger bow arm, a link having its outer end pivoted to the end of the outrigger bow arm and inclining upwardly to the upper end of the standard, a fixed pivot connecting said link and standard, said link having a free part extending in rear of its fixed pivot and constituting a cover supporting bow arm.

30. In testimony whereof, I affix my signature.
MAX BUCH.
